FIG. 6

UNITED STATES PATENT OFFICE.

CHARLES E. JEWETT, OF NORTH ANDOVER, AND FRED FITZGERALD, OF LAWRENCE,
MASSACHUSETTS.

BRUSH.

1,397,586.

Specification of Letters Patent.

Patented Nov. 22, 1921.

Application filed November 26, 1920. Serial No. 426,557.

To all whom it may concern:

Be it known that we, CHARLES E. JEWETT and FRED FITZGERALD, citizens of the United States, residing at North Andover and 5 Lawrence, respectively, in the county of Essex and State of Massachusetts, have invented certain new and useful Improvements in Brushes, of which the following is a specification.

10 Our invention relates to brushes, and is especially useful with what are known as dabbing brushes such as are used with combing machines, or any other type of bristle brush wherein certain sections of the 15 bristles wear out more rapidly than other sections.

In making and repairing bristle brushes, it is desirable to use machines such as Liebig filling machines, by which a staple looped 20 around a tuft of bristles is passed through a hole in a bristle block, so called, and forced into a plug therein or into a staple block behind it.

In dabbing and similar brushes, these 25 holes are close together and the holes are likely to be enlarged while being filled, while the plugs or the staple block are rapidly chewed up as the brush is repaired by pulling and driving staples.

30 Our construction consists essentially of a bristle block made of metal, preferably aluminum or some alloy similar to aluminum, having a plurality of bristle holes from face to back, and behind this a plurality of staple blocks instead of one staple 35 block or instead of plugs, preferably made of leather, cork, or other penetrable material which will not split when staples are driven into it.

40 Preferably also there is a back plate of skeleton aluminum construction and means to hold the parts together.

As dabbing brushes move at the rate of one thousand revolutions per minute, it is 45 highly necessary to combine lightness with strength.

In the drawings, Figure 1 is a perspective view of a complete dabbing brush embodying our preferred construction.

50 Fig. 2 is a perspective view showing the bottom or inside of the back plate.

Fig. 3 is a top or inside view of a bristle block having bristle holes and a rim embodying our construction.

55 Fig. 4 is a perspective view with part

broken away, showing our bristle block with its recess filled with a plurality of staple blocks.

Fig. 5 is a perspective view of part of a brush of a modified construction.

Fig. 6 is a sectional elevation on the line 6-6 of Fig. 1.

B represents the bristle block having a substantially flat face and back in which is a recess 20 formed by a rim 21 which extends all the way around. It also has suitable screw holes 22 and 23. From the face to the recess at the back are a plurality of bristle holes 24, each adapted to receive a tuft of bristles, such as C, which is looped 70 around a staple, such as 25. These holes 24 extend entirely through and are the same size throughout.

In the back of the bristle block B, preferably in the back recess 20 thereof, we place a plurality of staple blocks such as 30 and 31 which are preferably made of sole leather, wood, or other material adapted to have driven into it the staples 25 to retain tufts of bristles.

We can have two staple blocks of a shape such as shown at 30 and 31, or more, as shown by the dotted lines in Fig. 4, if it is desired. The staple blocks may be in a single layer or in two layers, as preferred. 85 Preferably these staple blocks are so arranged that one or more will include the parts of the brush which wear most rapidly so that when it is desired to renew the tufts of bristles from that section, the appropriate 90 staple block can be removed and replaced by a new one which will firmly hold new staples.

We prefer to hold the bristle blocks and staple blocks together by placing back of 95 them, resting on the rim 21, a back plate A shown as of the same shape and having a slot 10, by which it is attached to the machine, and recesses 11 to give it strength and lightness. It also has threaded screw holes 12 and 13 through which and through holes 22 and 23 the screws 42 and 43 pass, thereby holding the back plate and bristle block, with the inclosed staple blocks, together. These screws also pass through holes 32, 32, 105 33, 33, in the staple blocks.

In Fig. 5 we show a brush which may or may not be a dabbing brush, having a bristle block F with bristles C in the front or face of which are bristle holes similar to 24 to 110

receive bristles and staples. As shown, these staples are driven into anyone of a plurality of staple blocks, such as 50 and 51, which may be of leather or, preferably, of wood. 5 In this construction there is no back plate, but the bristle block and staple block are held together by means of screws such as 52, 52.

10 In a dabbing brush, we prefer to use leather, but with a brush such as shown in Fig. 5, wood or some more rigid material is preferable. In any case where the bristle block is not recessed or where a back plate is not used, a rigid penetrable material is 15 preferable.

We claim:

1. In a dabbing brush for combing machines, the combination of a bristle block formed with a recess and a plurality of 20 bristle holes extending from one face thereof to said recess, each hole being provided with

a tuft of bristles, a plurality of staple blocks of penetrable material in said recess, staples driven in said blocks and engaging the bristle tufts to retain the same in the 25 holes in the bristle block, and a backing plate extending over the backs of the staple blocks and secured to the bristle block.

2. In a dabbing brush for combing machines, the combination of a bristle block 30 formed with a plurality of bristle holes extending from the front face thereof to the back face, each hole being provided with a tuft of bristles, a plurality of staple blocks of penetrable material which rest against 35 said back face, staples driven in said blocks and engaging the bristle tufts to retain the same in the holes in the bristle block, and means to hold the staple blocks and the bristle block together.

CHARLES E. JEWETT.
FRED FITZGERALD.
